(57) **CLAIM**

The ornamental design for a fine mesh medical basket, as shown and described.

DESCRIPTION

FIG. 1 is an isometric view of a fine mesh medical basket showing my design;

FIG. 2 is a first side elevation view of the design of FIG. 1;

FIG. 3 is a top plan view of the design of FIG. 1;

FIG. 4 is a bottom plan view of the design of FIG. 1;

FIG. 5 is a second side elevation view of the design of FIG. 1;

FIG. 6 is a third side elevation view of the design of FIG. 1; and,

FIG. 7 is an enlarged isometric partial view of the first side corner of the design of FIG. 1, the dash-dash line depicts the area where the partial view is cut away from the fine mesh medical basket of FIG. 1 and forms no part of the claimed design.

The dot-dash-dot broken line in FIG. 7 depicts the boundary of enlarged view that forms no part of the claimed design.
